UNITED STATES PATENT OFFICE.

ODILON CHARETTE, OF FITCHBURG, MASSACHUSETTS.

LOOM SHUTTLE-BINDER.

1,192,825.

Specification of Letters Patent. Patented July 25, 1916.

Application filed September 13, 1915. Serial No. 50,491.

To all whom it may concern:

Be it known that I, ODILON CHARETTE, a citizen of the United States, residing at Fitchburg, in the county of Worcester and State of Massachusetts, have invented certain new and useful Improvements in Loom Shuttle-Binders; and I do declare the following to be a full, clear, and exact description of the invention, such as will enable others skilled in the art to which it appertains to make and use the same.

My invention relates to improvements in loom shuttle binders, and has for its object to provide means whereby shuttles contained in the shifting shuttle boxes will be reliably held therein against accidental movement until impelled outwardly by the picker-stick.

It has been found that during the course of operation of the loom, the usual springs on the shuttle binders require constant attention to maintain them at a correct tension so as to prevent any slipping of the shuttles. If the spring is too loose, the shuttle will frequently slip out, and if it is adjusted too tightly, the binder is pressed too close to the box to allow the shuttle to go completely into its cell; in either case a "smash" generally occurs, often doing considerable damage to the operating parts of the loom.

My invention is designed to overcome this objectionable feature of loom operation by providing means on the binders to be used in conjunction with the usual binder springs for retaining the shuttles. These binder springs are adjusted rather loosely so as to allow the shuttles to easily slide completely into their respective cells into the shifting shuttle boxes, where they can then be acted upon by my improvement to prevent them from slipping out until struck by the picker-stick.

The accompanying drawing fully illustrates my invention, wherein:

Figure 1 represents a rear side view of a shifting shuttle box and part of the lay end in which the said shuttle boxes rise and fall in the usual manner; Figs. 2 and 3 are longitudinal sectional views taken on the lines 2—2 and 3—3 of Fig. 1; and Fig. 4 is a detail transverse section through the binder, taken on the line 4—4 of Fig. 2.

In the drawing, I have shown a sufficient portion of the loom for illustrating my invention, L designating a portion of the lay

shaped to receive the usual shifting shuttle box frame on which the usual shuttle cells C are mounted, a binder 1 of the usual construction being positioned for coöperation with each of the cells. A shuttle box rod R is used for actuating the shuttle box frame. These binders 1 are of the usual construction for use on looms of the type illustrated, each of which comprises an arm 2 provided at one end with an ear 3 having an opening therethrough adapted to receive a pin 4 for pivotally connecting said binder to the shuttle box in the usual manner. A spring 5 usually designated as the binder spring, has one end adjustably secured to the shuttle box frame and has its opposite end disposed against the outer face of the binder at 6, and is used to press said binder toward the box so as to retain the shuttle therein before being acted upon by the picker stick. As hereinbefore stated, this binder spring requires frequent adjustment in order to obtain the correct tension of the binder to prevent slipping of the shuttle.

The foregoing described parts are common to all looms and form no part of my invention, they having been merely described for the purpose of clearly setting forth my improvement. As all the binders are similarly equipped with my improvement, but one will be described.

A circular opening 7 is formed through the binder substantially in its center, but slightly nearer to the pivoted end than the other, and is adapted to receive therethrough a detent 8 which is provided with a cam faced or hemispherical active end 9 for coaction with a seat 10 formed in one face of the shuttle. This seat 10 is of a shape to snugly receive the active end 9 of the detent and has its edges slightly rounded so as to readily pass over the detent when the shuttle is projected outwardly by the picker-stick. The opposite end of this detent is flattened, to which flattened end is secured by the rivet 11, a flat leaf spring 12 secured by the fastening devices, preferably in the form of rivets 13, to the binder adjacent its free end as clearly illustrated in Fig. 1 of the drawing. A pair of ribs 14 are formed on the outer face of the binder, one of said ribs being disposed on each side of the opening 7, extend longitudinally of the length of the binder and are adapted to receive therebetween the spring 12.

When the shuttle is knocked across the

loom through its raceway and into its compartment in the shifting shuttle box, it will force the binder outwardly against the tension of the binder spring, the detent, owing 5 to the shape of its active end 9, being at the same time depressed until the seat 10 arrives over the opening 7, when said detent will be projected into said seat and reliably hold the shuttle until actuated by the picker- 10 stick. While the shuttle will be held in the box against slipping or accidental discharge by the binder pressing on it and the detent resting in the seat, nevertheless, it is not so tightly held that the picker cannot readily 15 project it outwardly.

Because of its formation, the edge of the seat 10 will force the detent outwardly when the shuttle is struck by the picker-stick and allow the same to be projected out of the 20 box and through its raceway to its box on the other side of the loom where the operation will be repeated.

From the foregoing description, taken in connection with the accompanying drawing, 25 it is obvious that I have provided a very simple device for carrying out the object of my invention, and one which can be readily applied to binders already in use.

I claim:

30 1. In a loom shuttle binder having an opening therethrough, a detent disposed in said opening and having a hemispherical active end projecting beyond the inner face of said binder, the opposite end of said detent

being flat, longitudinally extending parallel 35 ribs disposed on the opposite sides of said opening, and a flat leaf spring secured by one end to the flat face of the detent and disposed between said parallel ribs, its opposite end being secured to the binder adjacent its free end. 40

2. In combination with a shifting shuttle box, of a shuttle having a hemispherical seat in one side, the edges of said seat being rounded, a shuttle binder having a circular 45 opening therethrough, a cylindrical detent slideable through said opening and having a hemispherical active end projecting beyond the inner face of said binder, the opposite end of the detent being flat, a flat leaf 50 spring secured by one end to the flat face of the detent, its opposite end being secured to the binder adjacent its free end, longitudinally extending parallel ribs disposed on the opposite sides of said opening and receiving 55 said spring therebetween, said detent moving into and out of said seat when the shuttle is actuated by the picker stick, and a spring for holding said binder in contact with said shuttle. 60

In testimony whereof I have hereunto set my hand in presence of two subscribing witnesses.

ODILON CHARETTE.
